UNITED STATES PATENT OFFICE

EMMETT F. CARTER, OF SCHENECTADY, NEW YORK, ASSIGNOR TO GENERAL ELECTRIC COMPANY, A CORPORATION OF NEW YORK

COMMUNICATION SYSTEM

Application filed August 15, 1927. Serial No. 212,880.

My invention relates to carrier current communication systems and more particularly to extension apparatus for use in connection therewith.

5 In connection with the operation of carrier current communication systems, such as are employed for communication over the lines of the usual power distribution system, it is desirable to extend the service of the carrier 10 system to parties remote from the carrier station.

One of the objects of my present invention is to provide an extension system whereby a party located at a point remote from the carrier station may control the carrier station to selectively call remote stations through the carrier channel and communicate therewith, and whereby the extension station may, similarly, be called from the remote stations 20 through the carrier channel.

A further object of the invention is to provide such an extension system in which both calling and signaling is effected over a single pair of line conductors extending between the carrier station and extension station.

In cases where it occurs that lines, either of the distribution system involved, or others, extend from the locality of the carrier station to that of the party to be served, it is desirable, for economic reasons, to effect communication from the remote party to the carrier station over lines which are mounted on the supports which are provided for the conductors of such power distribution systems. These lines usually have considerable voltage impressed thereon from the power conductors and are, therefore, unfit for low frequency signaling or control except as means 40 are provided for overcoming the noise, and singing, resulting from this interference.

Accordingly, a further object of my invention is to provide means whereby such conductors may be economically employed for 45 communication between the said party and the carrier station. Another purpose of my invention is to provide means whereby an operator at a remote station, such as that indicated, may utilize such power conductors 50 to control the carrier station in a manner

similar to that in which the operator at the carrier station itself may control it and with practically the same efficiency and facility. Still a further purpose of my invention is to provide means which are economical in construction and reliable in its operation whereby the service of the carrier system may be made available to the remote operator, notwithstanding that the intervening line is subject to severe interference of the type mentioned.

55 The novel features which I believe to be characteristic of my invention are set forth with particularity in the appended claims. My invention itself, however, both as to its 60 organization and method of operation, together with further objects and advantages thereof, may best be understood by reference to the following description taken in connection with the accompanying drawing, in 65 which the single figure represents an embodiment of my invention.

70 Referring to the drawing, B represents a carrier current signal station which is provided with the usual transmitting system 1 75 and receiving system 2 having associated therewith the usual telephone instrument 3, 4, by means of which an operator is enabled to communicate by means of carrier currents transmitted over a power distribution system 80. 5 or other carrier current channel with remote points located upon said channel. A represents an operator's station which is located at a point remote from the station B, but which may be interconnected therewith 85 by means of a pair of conductors 6 which are mounted upon supports which are primarily provided for power distribution conductors. Due to interference from the power distribution system these conductors have impressed thereon considerable voltage and are, therefore, unfit for the usual audio frequency or direct current communication or relay control. In accordance with my invention I provide means whereby signaling and control may be had over these conductors by 90 means of carrier current in one direction and by means of audio frequency currents in the other direction. By providing that the audio frequency currents have a suitable intensity 100

ratio with respect to the noise currents on the conductors 6, it will be seen that the effect of these noise currents upon the communication between the points A and B will be eliminated. It will also be seen that this is effected without encountering the difficult balancing and singing problems which are involved in connection with the use of two way audio repeating systems when utilized in connection with currents of this kind, and furthermore, the simple expedient of choke coils may be employed to separate the signals being transmitted in opposite directions at the different stations.

Accordingly, I provide at the station A a carrier current oscillation generator 7 and modulating device 8 therefor for supplying to the line 6 carrier current modulated with signaling current, the latter of which may be impressed upon the grid of the device 8 from the transmitter 9 of the operator's telephone. These currents may be transmitted through an output transformer 10, coupling condensers 11 and switching means 12 to the conductors 6. At the station B these currents will be received in a suitable tuned circuit 13 and impressed upon the detector 14, where they will be demodulated and the signaling currents supplied therefrom through a suitable audio amplifier 15 to the audio channel 16 of the transmitter 1. Connected in parallel with the audio channel 16 of the transmitter 1 is the secondary winding of a transformer 17, the primary winding of which is connected in parallel with the transmitter 4 of the telephone of the operator at the station B. The audio channel 18 of the receiver 2 at the station B is connected through a contact 19 and armature of the relay 20, the purpose of which will be later set forth, to the primary winding of an insulation transformer 21, the secondary winding of which is connected through suitable radio frequency choke coils 22 and switching means 23 to the extension conductor 6. The receiver of the telephone at the station A is connected through a pair of contacts 24 which are associated with the receiver hook to the secondary winding of an insulation transformer 25, the primary winding of which is connected through radio frequency choke coils 26 and switching device 12 to the extension conductor 6. The choke coils 22 and 26 offer high impedance to currents of carrier frequency and low impedance to currents of audio frequency. It will thus be seen that, with the apparatus as thus far described in its operative condition, the operator at the station A by speaking into his transmitter 9 may impress audio frequency currents upon the transmitting system 1 in the same manner as may be done by the operator at the station B. Likewise it will be seen that the operator at the station A, by listening at the receiver 27, may hear the signals received from the distribution system 5 by the

receiver 2 in the same manner as may be done by the operator at the station B.

I provide, in accordance with my invention, means whereby communication may be effected between the station B and the station A, and means whereby the station B may be controlled by the operator at the station A over the line 6 in the same manner as may be done by the operator at the station B. Describing more particularly the apparatus at the station A, 28 represents a transformer the primary winding of which is connected through the contacts of a relay 29 to a source of alternating current potential 30. A secondary winding of this transformer is adapted to energize the cathodes of the modulating device 8 and oscillator 7 through a circuit including conductors 31. 32 represents an electron discharge device, the cathode of which is energized from a winding 33 on the transformer 28. This device is utilized for the purpose of rectifying the alternating current from the source 30 and supplying a direct current potential to the anodes of the oscillation generator 7 and the modulator 8. For this purpose it is connected in a circuit extending from the anode of the discharge device 32 through the winding 34 of the transformer 30, conductor 35, resistance 36, contacts of a relay 37, conductors 31, space between the cathode and anode of the oscillation generator 7, primary winding of the transformer 10, radio frequency choke coil 38, conductor 39, smoothing reactor 40 to the cathode of the device 32. Since the anode and cathode of the device 8 are connected between the conductors 31 and the radio frequency choke coil 38 both of the devices 7 and 8 will be supplied with direct current potential from the device 32. The actuating coil of the relay 29 is adapted to be energized from a source of potential 41 through a pair of contacts 42 which are operated in accordance with the position of the receiver hook. Thus when the operator removes the receiver 27 from the hook the contacts 42 are moved to their closed position and the relay is energized to close its contacts, and thereby to energize the circuits of the devices 7 and 8. The actuating coil of the relay 37, the contacts of which are connected in the anode circuit of these devices, is likewise adapted to be energized from the source of potential 41 through a circuit including the conductor 43, source of potential 41, contacts 42 and dialing contacts 44. Thus the operator by removing the receiver from the hook and by operating the dial 45, thereby actuating the contacts 44, may energize the devices 7 and 8 to transmit carrier currents to the conductor 6 having interruptions therein corresponding to desired signals.

At the station B the detector 14 and amplifier 15 have their cathodes energized from the source of potential 46 through conductors 47. The anode circuit of the amplifier 130

15 is energized from a source of potential 48 through the primary winding of a transformer 49; and the anode circuit of the detector 14 is energized from the source of potential 48, through a circuit extending from the positive side of the source of potential through conductor 49, actuating coil of a relay 50 to the anode of the detector 14, space between the anode and cathode of this detector and thence back to the negative side of the source of potential 48. Thus when carrier currents interrupted in accordance with the operation of the contacts 44 are impressed upon the detector 14 the relay 50 is caused to respond, thereby closing its contacts and energizing a plurality of cascade connected relays 51, 52 and 20. The relay 51 which is adapted to be energized from the source of potential 46 through the contacts 20 of the relay 50 will then close its contacts, thereby actuating a relay 54 which is connected in a circuit extending from the negative side of the source of potential 46 through the lower contacts of the relay 51, actuating coil of the relay 54 to the positive side of the source of potential 46. The relay 54 may constitute the dialing relay of the transmitter 1 and is adapted by means of its lower contact to close the keying circuit 55 of the transmitter 1, thereby causing the transmitter to transmit carrier to the system 5 having interruptions therein in accordance with those received from the station A. The upper contacts of the relay 54 are connected in a circuit leading from the negative side of the source of potential 46 through these contacts to a pair of selecting devices 56 and 57 to the positive side of the source of potential. These selecting devices are adapted to close their contacts only in response to current impulses received in a particular code combination. Thus, for example, if the operator at the station A dials the number of the station B, the selector 56 will respond, thereby closing its contacts to actuate the signaling device 58 of the station B. The relay 52, which is adapted to be energized in response to the closing of the upper contacts of the relay 51 from the source of potential 48, is somewhat sluggish in opening its contacts and therefore will not follow the dialing interruptions. The relay 20 is operated in response to the closing of the contacts of relay 52, and thereby closes an energizing circuit of the transmitter 1 including conductors 59. Likewise, by means of the contact 19, this relay is adapted to connect the primary winding of the insulation transformer 21 directly to the audio frequency channel of the receiver 2.

Thus the operator at the station A by dialing the proper code number may actuate the signaling device 58 of the station B, or he may actuate the keying contacts of the relay 54 in a manner to key the output from trans-

mitter 1 in accordance with the code number of any station upon the distribution system 5. Means are likewise provided whereby any station upon the distribution system 5 may operate the signaling device of the station B, or that of the station A. To this end a relay 60 having contacts which are connected in parallel with the contacts of relay 54 is adapted to respond to carrier impulses received from the distribution system 5. Thus if these impulses correspond to the code number of the station B the selector 56 will be caused to respond to actuate the signaling device 58, whereas if the received impulses correspond to the code number of the station A the selector 57 will respond to close its contacts. Relay 61 is adapted to be energized from the source of potential 46 through the contacts of the relay 57 and when it is so energized it will close a circuit leading from the negative side of the source of potential 46 through the direct current side of a rotary converter 62, contacts of the relay 61, conductor 63, source of potential 48, right-hand conductor 47 and source of potential 46. This rotary converter, which is normally inoperative, will then be started and caused to supply alternating current through a circuit including conductor 64, alternating current side of the converter 61, conductor 65, lower contact and armature of the relay 20 and conductor 66 to the primary winding of the insulation transformer 21. Thus upon closing of the contacts of the relay 57, alternating current will be supplied through the transformer 21, extension circuit 6 and transformer 25 to the signaling device 67 of the station A.

The dialing contacts 68 of the telephone at the station B are connected in parallel with the lower contacts of the relay 51 and consequently they are effective to operate the dialing relay 54 and to key the transmitter in accordance with any desired code number. If the operator operates these contacts in accordance with the code number of station A, the selector 57 will respond to energize the rotary converter 62 in the same manner in which it does in response to the operation of the relay 60.

It will be seen that the operator at either the station A or the station B may operate the signaling device of the other station or that of any station upon the distribution system 5. Thus, for example, if the operator at the station B desires to talk with the operator at the station A, he removes his receiver 3 from the hook, thereby, through means not shown, closing the circuit 59 and energizing the transmitter 1. He then dials the number of the station A by means of the contacts 68. In response thereto the relays 54, 57 and 61 close their contacts, the latter of which energizes the rotary converter 62 causing it to supply signaling currents over the exten-

sion circuit 6 to the signaling device 68. The operator at the station A then removes his receiver from the hook, thereby energizing his transmitting circuit and causing it to supply carrier currents from the extension circuit

6 to the detector 14. When the operator at the station A speaks into the transmitter 9 these voice currents will be detected by the detector 14, amplified by the audio frequency amplifier 15 and supplied to the transmitter

1. A portion of the output current of the transmitter 1 will be supplied to the receiver 2 where they are detected and the signaling currents thereof impressed upon the receiver

15 3. Likewise, the operator at the station B, by speaking into his transmitter 4, will modulate the currents transmitted by the transmitter 1 which in turn will be detected by the receiver 2 and transmitted through the trans-

20 former 21, extension circuit 6 and trans- former 25 to the receiver 27. If any station upon the distribution system 5 is then in operative condition it will be seen that three

25 way communication may be had between the station A, B and the particular station upon the distribution system 5.

To prevent the noise resulting from the interference in the conductors 6 from interfering with the reception of signals from the station B at the station A, the receiver 2 is adapted to supply an audio output which has a desired intensity ratio to the noise currents of the conductor 6. In order that these currents will not be too great for the receiver 3 a resistance 69 is inserted in series therewith, and likewise a resistance 70 is inserted in circuit with the receiver 27 at the station A. It will be seen that this latter resistance will not only attenuate the signaling current but will also attenuate noise currents, thereby substantially eliminating the effect of the latter.

While I have shown and described a particular embodiment of my invention, it will, of course, be understood that I do not wish to be limited thereto since many modifications, both in the circuit arrangement and in the instrumentalities employed, may be made without departing from the spirit and scope 50 of my invention as set forth in the appended claims.

What I claim as new and desire to secure by Letters Patent of the United States, is:—

1. In a signaling system, a line, signaling stations at different points on said line, said line being subject to noise currents of magnitude sufficient to prevent satisfactory two-way audio communication between said stations, means for impressing a carrier wave modulated by signaling currents upon said line at one of said stations, means at another of said stations for detecting said signaling currents from said carrier wave, means at said other station for impressing signaling currents directly upon said line having a

desired intensity ratio with respect to noise currents appearing in said line, and means at said first station for attenuating said noise currents sufficiently to permit desired reception of the signal currents.

2. In a signaling system, a line, a carrier channel, a signaling station adapted to supply a carrier wave modulated with signaling currents to said line, a second station adapted to repeat said signaling currents to said carrier channel and means at said second station adapted to detect signaling currents received from said carrier channel and to supply said signaling currents directly to said line.

3. In a signaling system, a line, a carrier channel in addition to said line, a signaling station adapted to supply a carrier wave modulated with signaling currents to said line, a second station adapted to receive said signaling currents from said line and to repeat said signaling currents to said carrier channel, and means at said second station adapted to detect signaling currents received from said carrier channel and to supply said signaling currents directly to said line with a desired intensity relation to noise currents in said line, and means at said first station for attenuating said noise and signal currents.

4. In combination, a carrier channel, a carrier station having a transmitter and receiver adapted for two way communication over said channel, a second station, a line connecting said stations, said second station being adapted to supply a carrier wave modulated with audio frequency currents to said line and to receive audio frequency currents directly from said line, detecting means connecting said line with the audio frequency channels of said transmitter, and means connecting said line with the audio frequency channels of said receiver.

5. In combination, a carrier channel, a carrier station having a transmitter and receiver adapted for two way communication over said channel, a second station, a line connecting said stations, said second station being adapted to supply a carrier wave modulated with audio frequency currents to said line and to receive audio frequency currents directly from said line, detecting means connecting said line with the audio frequency channels of said transmitter and means responsive to received carrier for energizing said transmitter and connecting said line with the audio frequency channels of said receiver.

6. In combination, a carrier channel, a carrier station having a transmitter and receiver adapted for two way communication over said channel, a second station, a line connecting said stations, said second station being adapted to supply a carrier wave modulated with audio frequency currents to said line and to receive audio frequency currents directly from said line, detecting means con-

necting said line with the audio frequency channels of said transmitter, keying means for producing interruptions in the output from each of said stations, the keying means for said first station being operable responsive to interruptions in the carrier received from said second station, and means responsive to carrier received from said first station for connecting said line to the audio frequency channels of said receiver.

7. In combination, a carrier channel, a carrier station having a transmitter and receiver adapted for two way communication over said channel, a second station, a line connecting said stations, said second station being adapted to supply a carrier wave modulated with audio frequency currents to said line and to receive audio frequency currents directly from said line, detecting means connecting said line with the audio frequency channels of said transmitter and means connecting said line with the audio frequency channels of said receiver, a control circuit for said first station, and means responsive to carrier received from said second station for energizing said control circuit.

8. A transmission system comprising a power line adapted for the simultaneous transmission of power currents and signal waves, signal stations connected to said power line, means for one station to selectively call another station and to effect communication therewith, an extension station, conductors for connecting the extension station to one of said power line stations to permit calling and signaling over the same conductors, and means operated at said extension station through the associated signal station for selectively calling the power line stations and for communicating therewith.

9. In a transmission system, a power line for transmitting high tension power currents, signal stations connected to said power line, means at said signal stations for calling and signaling over said power line by carrier current waves, an extension station, conductors for connecting said extension station to one of said signal stations to permit calling and signaling over the same conductors, and means operated at said extension station through the associated signal station for selectively calling and signaling said signal stations connected to the power line.

10. In a transmission system, a power line for transmitting high tension power currents and carrier wave signal currents, signal stations connected to said power line, means comprising carrier current transmitting and receiving apparatus at each of said signal stations for selectively calling and for effecting communication between stations, an extension station, conductors for connecting said extension station to one of said signal stations to permit calling and signaling over the same conductors, and means at said ex-

tension station for calling and communicating with the associated signal station and for controlling the carrier current transmitting and receiving apparatus at the associated signal station to selectively call and signal the various signal stations.

11. In a power line carrier telephone system, a power line, signal stations connected to said line and having carrier current apparatus for calling other stations and for affecting telephone communication therewith, an extension station, conductors for connecting the extension station to one of said signal stations to permit calling and signaling over the same conductors, means controlled by signal stations connected to the power line for operating the carrier current apparatus at the signal stations associated with the extension station to selectively call either the extension station or the signal station associated therewith, and means operative upon removal of the receiver at the extension station from the switch hook for preparing the carrier current apparatus at the associated signal station for telephone communication between the extension station and signal stations.

12. A communication system comprising a power line adapted for simultaneous transmission of power currents and signal waves, carrier current signal stations connected to said power lines, means in each of said stations for selectively calling another station and to effect communication therewith, an extension station, line conductors extending between said extension station and one of said signal stations, and means for selectively calling any of said signal stations from said extension station and to call said extension station from any of said signal stations and to effect communication between the calling and called stations over said line conductors.

13. A transmission system comprising a power line adapted for the simultaneous transmission of power currents and signal waves, signal stations connected to said power lines, means for one station to selectively call another station and to effect communication therewith, an extension station, a single pair of line conductors extending between the extension station and one of said signal stations, and means at the extension station and associated signal station to effect both calling and signaling in both directions between said extension station and any of said signal stations over said single pair of line conductors.

14. In a transmission system, a power line for transmitting high tension power currents and carrier wave signal currents, signal stations connected to said power line, an extension station, conductors for connecting said extension station to one of said signal stations to permit calling and signaling over the

same conductors, carrier current transmitting and receiving apparatus at each of said signal stations, means at each signal station for controlling said carrier current apparatus to selectively signal and effect telephone communication with any other signal station, means at said extension station for operating the carrier current apparatus at the associated signal station to selectively call and to effect telephone communication with the other signal stations, and means for effecting telephone communication between the extension station and the associated signal station, said means utilizing the carrier current transmitting and receiving apparatus at the associated signal station to transmit telephone currents from said associated signal station to the extension station.

In witness whereof, I have hereunto set my
20 hand this 11th day of August 1927.
